BLANK CUTTING AND FEEDING MEANS FOR
PAPER CUP MACHINES

Leo M. Harvey, Los Angeles, Calif.

Application October 16, 1940, Serial No. 361,332

14 Claims. (Cl. 164—28)

This invention relates to equipment for forming and shaping articles of paper and the like and relates more particularly to a mechanism for supplying or feeding the paper material to a paper cup forming machine. A general object of this invention is to provide a practical, effective and dependable means for automatically cutting the paper cup blanks and for feeding the blanks between the dies of the cup making machine.

Another object of this invention is to provide a blank cutting and feeding means suitable for use on cup making machines of the character described and claimed in the United States Letters Patent No. 2,215,698, granted to me September 24, 1940.

Another object of this invention is to provide a blank forming and feeding means for a paper cup machine which continuously draws a web of paper from a paper roll, automatically cuts the web into disc-shaped cup blanks and feeds the blanks between the dies of the cup forming machine in synchronism with the die action.

Another object of this invention is to provide a blank cutting and feeding mechanism embodying a novel and particularly efficient, continuously operated, cutting means which cuts the disc-shaped blanks from the advancing paper strip or web.

Another object of this invention is to provide a blank cutting and feeding means of the character referred to embodying a simple, dependable conveyor means or blank advancing means which moves the cut blanks to positions between the machine dies in synchronism with the reciprocating die elements without interference by the continuously moving paper being cut at the cutting means.

A further object of this invention is to provide a blank cutting and feeding means for a paper cup machine which operates continuously and automatically without the attention of an attendant. The cutting and feeding means of the present invention is entirely automatic and only requires attention when the large paper supply roll becomes exhausted.

The various objects and features of my invention will be fully understood from the following detailed description of a typical preferred form and application of the invention, throughout which description reference is made to the accompanying drawings, in which:

Fig. 1 is a vertical detailed sectional view of the mechanism of the present invention and the adjacent parts of the cup machine. Fig. 2 is an enlarged fragmentary vertical sectional view of

the cutting and blank advancing means with the adjacent movable fluting die appearing in broken lines, illustrating the manner in which the scrap paper is removed and the manner in which the advancing blank material may ride over the cut blank. Fig. 3 is a horizontal detailed sectional view taken substantially as indicated by line 3—3 on Fig. 2. Fig. 4 is an enlarged fragmentary vertical detailed sectional view taken substantially as indicated by line 4—4 on Fig. 1 and Fig. 5 is a stretch out or development of the cutter roller.

The blank cutting and feeding mechanism of the present invention is adapted for use in connection with shaping or forming machines of various kinds and may be modified to some extent to adapt it for use in different situations and in connection with different machines. In the drawings I have illustrated the mechanism of the invention in connection with a paper cup forming machine of the character disclosed in my issued patent referred to above. It is to be understood that the invention is not to be construed as limited or restricted to this particular form and application of the invention but is to be taken as including any features and modifications that may fall within the scope of the claims.

The portion of the cup forming machine illustrated in the drawings comprises a frame 10 supporting and housing the various machine elements. A pair of spaced horizontal shafts 11 is provided in the frame 10 and carries mating cams 12 for operating and timing the various dies, etc. of the machine. The shafts 11 are continuously operated or driven when the machine is in operation. The cup shaping mechanism includes a stationary fluting die 13 and a movable fluting die 14 below and aligned with the die 13. Male and female shaping dies 15 and 16 telescope within or extend through the dies 13 and 14, respectively. The margin of the shiftable flute forming die 14 has a horizontal flat table part 17 for the reception of the cup blank. Spaced upstanding pins 18 are provided on the table part 17 to center or locate the cup blanks on the axis of the die assembly. An annular series of rods 19 is shiftably guided in openings 20 and are provided at their upper ends with weights 21. The rods 19 project downwardly around the stationary die 13 and are engaged by the paper blank as the die 14 moves upwardly, serving to maintain the blank in position and to assist in the fluting operation.

The dies 13 and 14 are spaced one above the

other as illustrated in Fig. 1 before each cup shaping operation and the blank cutting and feeding means of the invention serves to introduce a paper blank between the dies 13 and 14 immediately preceding the cycle of operations of the dies 13, 14, 15 and 16. The present invention is not primarily concerned with the details of the dies, the die operating means, etc. and reference is hereby made to my above-identified issued patent for a full disclosure of such elements.

The improved blank forming and feeding means of the invention may be said to comprise, generally, a supporting means or body 22, a paper supply 23, means 24 for continuously drawing paper from the supply 23 and for cutting it into cup blanks B, and means 25 for conveying or shifting the blanks B to the dies 14 and 15.

The body 22 serves to carry the various elements of the mechanism. In the particular case illustrated the body 22 is a channel-like member having a lower wall 26 and two side walls 27 extending upwardly from the lower wall. Flanges 28 on the upper edges of the side walls 27 may be bolted to the machine frame 10 to mount the equipment. A substantially horizontal shelf or table 29 is spaced above the lower body wall 26. The table 29 may be supported by angle irons 30 fixed to the side walls 27. The table 29 is positioned to be in the horizontal plane occupied by the die part 17 when the die 14 is in position to start the cup forming operations. As best illustrated in Fig. 1 the inner edge of the table 29 is at or immediately adjacent the edge of the die part 17 and the outer edge of the table is spaced inwardly from the outer side of the body 22.

The paper supply 23 is adapted to carry a large quantity of paper and is such that the means 24 may continuously feed, draw or advance the strip or web or paper P. The paper supply 23 may comprise a pair of horizontally spaced brackets 31 mounted on the frame 10 of the machine. The brackets 31 project upwardly and outwardly and their upper ends have notches 32 for receiving a shaft 33. The shaft 33 turnably or rotatably carries a supply roll R of the paper web. There may be a continuous web or strip of waxed paper or paper cut material wound in the roll R. The roll R is arranged so that the paper P passes from its inner side to the cutting and feeding means 24. Means is provided for tensioning the paper P and for directing the paper to the means 24 in the most advantageous manner. Tensioning arms 34 are pivotally carried by the shaft 33 and project toward the machine. A roller 35 is rotatably carried between the spaced arms 34 to bear downwardly on the paper P between the roll R and the means 24. Tension springs 36 are connected between the brackets 31 and the arms 34 to urge the arms downwardly. The springs 36 maintain a suitable tension on the paper P. The roller 35 bearing downwardly on the paper P causes the paper to pass substantially vertically to the means 24.

The means 24 operates to continuously draw or advance the paper P from the supply roll R and to cut the paper into the disc-shaped cup blanks B. The means 24 includes a cutting roller 37 and an abutment roller 38. The rollers 37 and 38 are fixed to vertically spaced horizontal shafts 39, which in turn are rotatably carried by suitable bearings 40 on the side walls 27. The axes of the shafts 39 occupy a common vertical plane located beyond the outer edge of the table 29. The cutting roller 37 and the abutment roller

38 are both positively driven at a given or predetermined speed or speeds relative to the speed of operation of the machine to advance the paper P and cut the blanks B at the correct rate. In the construction illustrated there is a chain and sprocket drive 41 between one of the cam shafts 11 and the shaft 39 of the abutment roller 38 and a gear drive 42 is provided between the two shafts 39 to rotate the rollers 37 and 38 at the same speed. The abutment roller 38 is formed of a hard material, such as steel, or the like. The feeding and cutting roller 37 has a body 43 of rigid or unyielding material.

A knife or cutter 44 is provided on the body 43 of the roller 37. The cutter 44 is shaped to give the blanks B the desired configuration. In the embodiment of the invention illustrated the knife 44 is in the form of a developed circle on the cylindrical periphery of the roller body 43 operable to form or cut disc-shaped blanks B. As illustrated in Fig. 5 the knife or cutter 44 extends completely around the roller body 43 and is formed to have, what may be termed diametrically opposite peripheral portions merge at a point or line 45. The base of the cutter or knife 44 may be embedded in the roller body 43 and the knife is fixed to the roller body. The cutting edge of the cutter 44 is beveled or of V formation. The knife 44 has accurate co-action with the abutment roller 38. The roller 38 has a truly cylindrical periphery ground or finished to cooperate with the edge of the cutter 44 in such a way that the cutter completely cuts through the paper P throughout the extent of its curved edge. As illustrated in Figs. 1 and 2 of the drawings, the knife or cutter 44 cooperates with the abutment roller 38 in a horizontal plane adjacent to and slightly above the plane of the table 29.

In accordance with the invention the cutter roller 37 embodies a layer or shell 46 of compressible resilient material to assure the full effective advancement of the paper P and blanks B, to dependably clear the paper of the cutter 44 and to eject the cut paper blanks B and paper scraps S. The shell 46 is formed of rubber, synthetic rubber, rubber compositions, or the like, having substantial resiliency and compressibility and having desirable limited adherence to the paper P. The shell 46 may cover the periphery of the roller body 43. The thickness of the shell 46 is such that the shell protrudes beyond the cutting edge of the cutter 44 so that the shell is compressed through contact with the abutment roller 38. As best illustrated in Fig. 2 of the drawings, the paper P from the supply roll R is tightly held against a considerable portion of the rubber shell 46 to be effectively advanced and the paper is tightly gripped between the abutment roller 38 and the compressed resilient shell 46 to be positively advanced by rotation of the rollers 37 and 38. The surface of the shell 46 may be finished to have effective traction or advancing engagement with the paper P.

The action of the shell 46 in freeing or clearing the paper from the cutter 44 is important. The shell 46 is compressed below or beyond the edge of the cutter 44 by the abutment roller 38 at the point or points of engagement of the cutter with the roller 38, this compression of the shell below the knife edge being due to the paper P which is received between the shell and the rigid abutment roller 38. As the knife portions and the shell 46 leave the abutment roller 38, by reason of the rotation of the rollers, the re-

silient shell returns to its original shape and diameter. This expansion or restoration of the resilient shell 46 forces the paper outwardly out of cooperation with the cutter 44, thus fully freeing or clearing the paper from the cutter. The rubber shell 46 also operates to push or advance the cut blanks B and paper scraps S forwardly from between the rollers 37 and 38 as the paper is cut.

The invention provides novel means for handling and directing the paper blanks B and the cuttings or scraps S so that they do not pile up or interfere with the continuous cutting action. The resilient shell 46 is reduced in thickness from the line of joinder 45 of the knife 44 forwardly some distance to a line such as 48 in Fig. 5. This leaves the advancing side of the knife 44 exposed at the line 45 and this portion of the knife acts as an advancing or feeding shoulder. The exposed portion of the knife 44 at and adjacent the line 45 pushes the freed blank B forwardly as the blank leaves the rollers 37 and 38. Fig. 2 of the drawings illustrates this action of the exposed knife 44 at the line 45. As shown in this figure the face of the shell 46 immediately behind the line 45 of the knife 44 constitutes an extension of the above mentioned shoulder so that the knife 44 and this shoulder portion of the shell 46 may both act in pushing or shifting the blank B forwardly from between the rollers.

A yoke or bridge 49 is secured to the opposite side walls 27 and extends horizontally over the table in spaced relation to the table surface. A substantially central spring finger 50 is secured to the bridge 49 and projects toward the rollers 37 and 38. The spring finger 50 is curved downwardly and toward the rollers 37 and 38 and is then curved upwardly to have its outer end adjacent and opposing the periphery of the abutment roller 38. The finger 50 thus presents a curved surface which is engageable by the advancing edge of the cup blank B as the blank moves from between the rollers 37 and 38. The spring finger 50 directs the blank B downwardly to move across the flat face of the table 29 and prevents the blank from buckling or curling at its center.

The means for clearing and removing the paper cuttings or scraps S comprises spring fingers 51 projecting upwardly through slots 52 in the table 29. The slots 52 are formed adjacent the opposite side edges of the table 29 adjacent or in front of the rollers 37 and 38. The spring fingers 51 may be attached to blocks 53 on the under side gers 54 curve downwardly to extend through the slots 52 to project above the surface of the table 29. The forward or free ends of the spring fingers 51 curve downwardly to extend through the slots 52 so that they are not engaged by the advancing paper. The substantially triangular paper cuttings or scraps S ride up on the fingers 51 as they leave the rollers 37 and 38 and are thus cleared of the blanks B which are directed downwardly by the centrally disposed finger 50 to ride across the face of the table 29. It is to be observed that the merging portion of the cutter 44 at the point or line 45 provides for the formation of separate or distinct scraps S between the adjacent portions of the blanks B. Further, it is to be observed that the width of the paper P is slightly less than the diameter of the cutter or knife 44 leaving short straight edges E on the blanks B and assuring the complete separation of the scraps S which are produced during the successive cutting operations. These entirely

separate scraps S are readily cleared and removed.

Suitable means may be provided for removing the paper scraps S from the table 29. The body 55 may carry hoppers 54 provided with chutes 55 opening upwardly at each side of the table 29. Air jets 56 are provided above the table 29 and are directed downwardly and outwardly to blow the freed cuttings or scraps S into the chutes 55. Air under pressure is continuously supplied to the jets 56 by an air line 57. The jets 56 are arranged and directed so that the air streams do not interfere with or shift the cup blanks B.

The blank conveying or advancing means 25 operates to quickly shift the finished blanks B to the correct positions between the dies 13 and 14 during the short cycle period during which the dies are separated before initiating their cup fluting or forming operations. The means 25 includes a shaft 58 arranged below the table 29 adjacent the inner edge of the table. The shaft 58 is rotatably carried by suitable bearings 59 in the side walls 27 and is continuously positively driven. In accordance with the invention the shaft 58 is rotated at a faster rate than the rollers 37 and 38. Any suitable means may be provided for driving the shaft 58. In the case illustrated there is a speed increasing gear train 60 between the shaft 39 of the roller 37 and the shaft 58. A pair of blank advancing wheels or rollers 61 is provided on the shaft 58, see Fig. 4. The rollers 61 may be secured to or may be parts of a common hub 62 which in turn is fixed to the shaft 58. The peripheral portions of the rollers 61 are received by slots 63 in the table 29. The peripheries of the wheels or rollers 61 are concaved or provided with rounded grooves 64.

The means 25 further includes wheels or rollers 65 for co-acting with the rollers 61 at certain operation periods to cause the rapid advancement of the cup blanks B to their positions between the dies 13 and 14. The rollers 65 are carried by a lever arm 66 disposed above the table 29. A shaft 67 on the lower end of the arm 66 supports the rollers 65 for free rotation. The peripheries of the rollers have rounded ridges 68 which conform to the grooves 64 in the rollers 61. When the arm 66 is in its down or operative position the ridges 68 extend through the slots 63 and co-act with the grooves 64 in the continuously rotating rollers 61 to produce sudden positive advancement of the cup blank B and to corrugate or groove the blank along spaced parallel lines to prevent the central portion of the blank from bulging or buckling.

A detent or gravity stop finger 69 may be hinged or pivoted to the arm 66 to assist in holding the cup blanks B down upon the table 29 and to prevent the blanks from prematurely travelling beyond the intermediate blank position. A pivot pin 70 may secure the finger 69 to the arm 66 so that the finger is free to hang from the arm. The finger 69 is spaced between the rollers 65 and extends downwardly and forwardly relative to the movement of the blanks B. The lower portion of the finger 69 is smooth and rounded to effectively direct and stop the blanks B. The detent finger 69 may be made quite heavy so that its weight is sufficient to stop the blanks B as required.

Cam means is provided for operating the roller arm 66 in timed relation to the cup forming machine. The outer or upper end of the arm

66 is fixed to a horizontal shaft 72 turnably carried in suitable bearings 72 in the side walls 27. A split or divided arm 73 is fixed to the shaft 71 adjacent one of the side walls 27. A cam roller 74 is rotatably mounted in the lower portion of the arm 73. A disc cam 75 is fixed to the abutment roller 38 at one end of the roller and is engageable by the wheel or roller 74. The surface of the cam 75 is plain and cylindrical except for a depressed or flat face 76. The engagement of the roller 74 with the cylindrical surface of the cam 75 holds the arm 66 in a position where the rollers 65 are above and clear of the blank B on the table 29. When the surface 76 reaches the roller 74 the arm 66 is free to swing downwardly so that the rollers 65 engage the blank B and co-act with the rollers 61. A spring 77 is attached to an arm 78 fixed to the shaft 71 to urge the arm 66 downwardly when the cam roller 74 is in cooperation with the surface 76. The spring 77 urges the arm 66 downwardly with sufficient force to cause the co-acting rollers 61 and 65 to positively advance the blank B and to press or form the ridges in the blank. When the cam surface 76 leaves the roller 74 the arm 66 is again raised to clear the rollers 65 so that the next blank B is free to pass under them for engagement by the gravity finger 69 only. The rotative position of the cam face 76 and the extent of the cam face 76 are such that the rollers 61 and 65 co-act to quickly shift the cup blank B from the table 29 to the position between the dies 13 and 14 during the short period when the dies are separated prior to the initial cup shaping die action and the movement of the blank brings the edge of the blank against the centering or locating pins 18.

The means 25 further includes a supplemental blank advancing means which imparts a final positive movement to the blank B to assure its proper positioning between the dies 13 and 14. This means includes a horizontal shaft 79 spaced above the inner part of the table 29 and turnably carried in suitable bearings 80 on the side walls 27. A pair of horizontally spaced depending blank advancing fingers 81 is fixed to the shaft 79. The fingers 81 may be fixed to the shaft 79 by suitable collars 82. The fingers 81 project downwardly and away from the die assembly at each side of the arm 66, when in their normal inoperative positions, and the lower ends of the fingers are normally above and clear of the table 29. Cam means is provided for operating the fingers 81 toward the die assembly during the cyclic period when the blank B is moving onto the die part 17. The fingers 81 are proportioned to engage the trailing edge of the blank B as the blank is moving between the dies 13 and 14 and slots 83 are provided in the table 29 to receive the lower parts of the fingers when the fingers are in operation.

The cam means for operating the fingers 81 includes a lever arm 84 fixed to a collar 82 and a link 85 pivotally connected with the lever arm 84. A shaft 86 is spaced above the roller 38 and is turnably carried by suitable bearings on the side walls 27. A crank arm 87 is fixed to the shaft 86 and the link 85 is pivotally connected with the arm 87. A second crank arm 88 is fixed to the shaft 86 and carries a cam roller 89. A disc-like cam 90 is fixed to the abutment roller 38 to cooperate with the roller 89. The cam 90 may be adjacent the cam 75 and has a plain cylindrical surface except for a depression 91.

When the depression 91 reaches the roller 89 the fingers 81 are free to swing downwardly and toward the die structure. Spring means is provided for actuating the fingers 81 when released as just described. The springs 77, described above, may be connected with an arm 93 on the arm 84 to actuate the fingers 81. The position and extent of the depression 91 are such that the fingers 81 are actuated to impart a final positive movement to the blank B, advanced onto the die part 17 by the rollers 61 and 65, this final movement being sufficient to engage the blank against the centering pins 18. It is to be understood that the advancement of the blank B between the dies 13 and 14 by the rollers 61 and 65 and by the fingers 81 is quite rapid.

The feed means 25 just described may be timed so that there is little or no interruption in the advancement of the blanks B after the blanks 20 have been cut clear. Thus the cut blanks B may be pulled ahead to the cup shaping position immediately reducing or eliminating the possibility of blank interference between the cutting means 23 and the cup shaping dies.

It is believed that the operation of the blank forming and feeding mechanism of the invention will be readily understood from the foregoing detailed description. With the cup forming machine in operation the rollers 37 and 38 are continuously rotated so that the paper P is continuously drawn from the supply roll R. The knife or cutter 44 on the continuously rotating roller 37 successively forms or cuts the blanks B which are fed and directed onto the table 29 by 30 the action of the resilient shell 46 and the finger 51, all as above described. The means 25 operates in synchronism with the blank cutting means 24 and in synchronism with the cup forming machine so that the rollers 61 and 65 and the fingers 81 advance the cut blanks B to centralized positions between the dies 13 and 14 during the period when the dies are separated before co-acting to flute the blank. The mechanism is entirely automatic in operation and does not require attention. The paper P is easily trained through the mechanism when a new supply roll R is installed and this is the only conditioning or attention required.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. In a mechanism of the character described, an abutment element, a rotatable roller, a cutter on the roller adapted to coact with the abutment element to cut blanks from sheet material, and a resilient compressible layer on the roller engaged against the opposite sides of the cutter and of sufficient thickness to be compressed through contact with the abutment element and operable through its resiliency to free the blanks from the cutter as the cutter moves out of coaction with the abutment element, said layer having a portion of reduced thickness at a part of the cutter providing a shoulder which pushes the blanks away from the roller as formed.

2. A feed for a paper cup machine having a supply web of sheet material and cup shaping dies spaced apart prior to actuation, comprising means for continuously drawing the web from the supply and cutting the web into cup blanks,

and intermittently operating means for inserting the blanks between the dies.

3. A feed for a paper cup machine having a supply of paper in strip form and having cup shaping dies spaced apart prior to actuation and thereafter performing cup-shaping operations and returning to their spaced apart relation, the feed comprising continuously operating means for withdrawing the paper strip from the supply and cutting cup blanks therefrom, and intermittently operating means for introducing said blanks between the dies prior to their operation.

4. A feed for a paper cup machine having cup shaping dies spaced apart prior to actuation and thereafter performing cup-shaping operations and returning to their spaced apart relation, the feed comprising means for supporting a supply of paper in strip form, means for drawing the paper from the supply and for cutting cup blanks therefrom including a pair of continuously rotatable rollers between which the paper is trained, a cutter on one roller coacting with the other roller to cut said blanks, and means for rotating the rollers, and intermittently operating conveyor means for shifting said blanks between the dies.

5. A feed for a paper cup machine having a supply of paper in strip form and having cup shaping dies spaced apart prior to actuation and thereafter performing cup-shaping operations and returning to their spaced apart relation, the feed comprising means for drawing the paper from the supply and for cutting cup blanks therefrom including a pair of rotatable rollers between which the paper is trained, a cutter on one roller coacting with the other roller to cut said blanks, and a compressible resilient layer on the first named roller compressed through contact with said other roller and operating by its resiliency to free the blanks from the cutter as the cutter turns away from said other roller, and means for continuously rotating the rollers, and conveyor means for shifting said blanks between the dies.

6. A feed for a paper cup machine having cup shaping dies spaced apart prior to actuation and thereafter performing cup-shaping operations and returning to their spaced apart relation, the feed comprising means for supporting a supply of paper in strip form, means for drawing the paper from the supply and for cutting cup blanks therefrom including a pair of rotatable rollers between which the paper is trained, a cutter on one roller coacting with the other roller to cut said blanks, and means for continuously rotating the rollers, and conveyor means for shifting said blanks between the dies, the conveyor means including a rotating conveyor wheel at one side of the blank leaving the rollers, a shiftable idler wheel at the other side of the blank, and means for shifting the idler wheel against the blank so that the blank is engaged between the wheels and advanced thereby.

7. A feed for a paper cup machine having cup shaping dies spaced apart prior to actuation and thereafter performing cup-shaping operations and returning to their spaced apart relation and having means for cutting cup blanks, the feed including a rotating conveyor wheel at one side of the blank leaving the cutting means, a shiftable idler wheel at the other side of the blank, and means for shifting the idler wheel against the blank so that the blank is engaged between the wheels and advanced thereby, one wheel having a groove and the other having a ridge

whereby the blank is provided with a ridge as it is fed to the dies.

8. A feed for a paper cup machine having cup shaping dies spaced apart prior to actuation and thereafter performing cup-shaping operations and returning to their spaced apart relation and having rotatable rollers for drawing paper from a supply and for cutting cup blanks therefrom, the feed comprising a wheel positioned to be at one side of the blanks which leave the rollers, means for rotating the wheel at a faster rate than the rollers, a shiftable idler wheel at the other side of the blanks, and means for moving the idler wheel into and out of engagement with the blanks whereby the wheels coact to advance the blanks.

9. A feed for a paper cup machine having cup shaping dies spaced apart prior to actuation and thereafter performing cup-shaping operations and returning to their spaced apart relation and having rollers for drawing paper from a supply and for cutting cup blanks therefrom, the feed comprising intermittently coacting rotatable wheels for acting on the blanks after they leave the rollers and shifting the blanks between the dies, and swinging finger means for completing the advancement of the blanks.

10. A feed for a paper cup machine having cup shaping dies spaced apart prior to actuation and means for cutting the cup blanks, said feed including a table for receiving the blanks as they leave the cutting means, the table having an opening, a continuously rotating conveyor wheel under the opening, a swinging arm above the table, a wheel on the arm normally clear of the table and blanks, and means for swinging the arm down against the blanks whereby the blanks are gripped between the wheels to be shifted between the dies thereby.

11. In a machine of the character described having a blank cutting means and die means, the combination of, a table for receiving the blanks from the cutting means, two rollers, one above the table, the other below the face of the table, means for rotating one of the rollers, means supporting the other roller for movement toward and away from the rotating roller, and means for moving the movable roller into and out of engagement with the blanks so that the coacting rollers advance the blanks from the cutting means to the die means.

12. In a machine of the character described having a blank cutting means and die means, the combination of, a table for receiving the blanks from the cutting means, the table having an opening, a rotating wheel below said opening, a swinging arm above the table, a rotatable wheel on the arm, and means for swinging the arm to bring the last named wheel against the blanks over the opening so that the wheels coact to advance the blanks from the cutting means to the die means.

13. In a machine of the character described having a blank cutting means and die means, the combination of, a table for receiving the blanks from the cutting means, two rollers, one above the table, the other below the face of the table, means for rotating one of the rollers, means supporting the other roller for movement toward and away from the rotating roller, means for moving the movable roller into and out of engagement with the blanks so that the coacting rollers advance the blanks from the cutting means to the die means, and a swinging finger means above the table for acting on the blanks

to complete their advancement into the die means.

14. In a machine of the character described having a blank cutting means and die means, the combination of, a table for receiving the blanks from the cutting means, the table having an opening, a rotating wheel below said opening, a swinging arm above the table, a rotatable wheel

on the arm, means for swinging the arm to bring the last named wheel against the blanks over the opening so that the wheels coact to advance the blanks from the cutting means to the die means, and a gravity finger on the arm for holding the blanks against the table.

LEO M. HARVEY.
